(57) **CLAIM**

The ornamental design for a control knob for kitchen appliances, as shown and described.

DESCRIPTION

FIG. 1 is a perspective view of one embodiment of a control knob for kitchen appliances according to the present invention;

FIG. 2 is a front view thereof;

FIG. 3 is a first side view thereof;

FIG. 4 is a second side view thereof, opposite the first side view;

FIG. 5 is a third side view thereof;

FIG. 6 is a fourth side view thereof; opposite the third side view;

FIG. 7 is a perspective view of one embodiment of a control knob for kitchen appliances according to the present invention;

FIG. 8 is a front view thereof;

FIG. 9 is a rear view thereof;

FIG. 10 is a first side view thereof;

FIG. 11 is a second side view thereof, opposite the first side view;

FIG. 12 is a third side view thereof;

FIG. 13 is a fourth side view thereof, opposite the third side view;

FIG. 14 is a perspective view of one embodiment of a control knob for kitchen appliances according to the present invention and being located on a kitchen appliance shown in broken line for context;

FIG. 15 is a front view thereof;

FIG. 16 is a rear view thereof;

FIG. 17 is a first side view thereof;

FIG. 18 is a second side view thereof, opposite the first side view;

FIG. 19 is a top view thereof; and,

FIG. 20 is a bottom view thereof.

(Continued)

The broken lines shown in the drawings represent unclaimed portions and form no part of the claimed design.
